UNITED STATES PATENT OFFICE

CHARLES E. VAWTER, OF PHILADELPHIA, PENNSYLVANIA, ASSIGNEE TO DUBILIER
CONDENSER CORPORATION, OF NEW YORK, N. Y., A CORPORATION OF DELAWARE

ELECTRICAL CONDENSER

Application filed March 21, 1925. Serial No. 17,376.

This invention relates to improvements in electrical condensers, particularly condensers for use in connection with radio apparatus.

An object of this invention is to provide a condenser of the type adapted to carry a high electrical resistance, generally termed a grid-leak resistance, the supports for the resistance being directly connected to the elements to be of opposite potential in the condenser, such supports being preferably constituted of integral extensions of said elements.

The nature and objects of the invention are fully set forth in the following description and accompanying drawings; but the disclosure is illustrative only and I may resort to all variations of structure that are embraced within the meaning of the terms of the appended claims.

On the drawings,

Figure 1 is a longitudinal section of a condenser according to my invention;

Figure 2 is a top plan; and

Figure 3, an end view seen from the left of Figures 1 and 2.

The same numerals identify the same parts throughout.

The body of the condenser comprises electrically conductive elements 1 and 2 which overlap each other, these elements of course to be of different potential in practice, and being electrically insulated from each other. The elements 1 and 2 project from the opposite extremities of the body of the condenser, the portions which project being bent upward or laterally with respect to the body of the condenser, such portions being indicated by the numerals 3 and 4, and belonging to the elements 1 and 2 respectively. The bent ends of the portions 3 and 4 have holes 5 to receive the pointed ends of an electrical resistance member 6. The extensions 3 and 4 make terminals for the condenser and enable both the condenser and the resistance to be connected to the opposite extremities of an electrical circuit.

The elements 1 and 2 are of course separated by a suitable insulation indicated at 7, this insulation to be mica or any other suitable substance. The remaining two faces of the elements 1 and 2, that is, all the portions which overlap, are covered with sheets of insulation 8 which may be oiled linen, for example, and encircling the overlapping portions of the two elements is a clamp 9 preferably of metal which serves as means for retaining the two elements in operative relation to each other. This clamp 9 is made tight enough to hold the elements 1 and 2, and the insulation 7 and 8 tightly together.

The extensions 3 and 4 are perforated to provide apertures 10 at the opposite ends of the body of the condenser, and between these ends and the points where the extensions are bent upward to mount the member 6. The apertures 10 enable fastening means to hold the condenser in required position. The parts of the extensions which are bent for such a purpose are cut out to provide tongues or lugs 11, and to these lugs the conductors of an electric circuit, to include a condenser, may be secured by soldering or in any other suitable manner.

The resistance member 12 may be of the usual type comprising a fibre tube with a conductor of high resistance therein connected to pointed metallic ends 12 which enter apertures 5.

The elements 1 and 2 will of course be thick and strong enough to make the extensions 3 and 4 sufficiently rigid to engage the resistance member 6 firmly. At the same time, the bent portions of the extensions 3 and 4 will be sufficiently resilient to enable them to be moved far enough away from each other to receive the resistance 6 between them.

Having described my invention, what I believe to be new and desire to secure and protect by Letters Patent of the United States is:—

1. An electrical condenser comprising at

least two overlapping elements of different polarity, said elements each projecting from the opposite ends of the body of the condenser to a material extent, each element being bent 5 sidewise exterior to said body, and being shaped at its extremities to engage an electrical resistance member to be mounted on the condenser, each element having a lug cut out of its bent portion to connect with one extremity of an electrical circuit, a clamp encircling the overlapping elements and hold them in operative relation, and insulation between said elements and said clamp, said elements also being perforated adjacent the 10 lugs to enable the condenser to be held in operative position.

2. An electrical condenser comprising at least two overlapping elements of different potential separated by dielectric material, 20 each of said elements having an extension to engage an electrical resistance member to be mounted on the condenser, and means for retaining said elements in operative relation to each other.

25 3. An electrical condenser comprising at least two overlapping elements of different potential separated by dielectric material, each element having a terminal projecting out of the body of the condenser, said terminals being at opposite ends thereof, each terminal being shaped to engage an electrical resistance member to be mounted on the condenser, and retaining means encircling said overlapping elements to secure them in operative relation to each other.

4. An electrical condenser comprising at least two overlapping elements of different potential separated by dielectric material, each element having a terminal projecting 40 from the body of the condenser, the terminals being at opposite extremities thereof, each terminal being bent sidewise with respect to said elements and being shaped at its ends to engage an electrical resistance member to be mounted on the condenser, each terminal having a lug to connect with one extremity of an electrical circuit, a clamp encircling the overlapping elements and hold them in operative relation, and insulation between said elements and said clamp.

5. An electrical condenser comprising a plurality of armatures of opposite polarity separated by dielectric material, the armatures being adapted to support an electrical 55 resistance element and to connect the same in circuit with the condenser.

6. An electrical condenser having a plurality of armatures of opposite polarity in the form of plates, said plates extending from 60 the condenser body and serving as the sole means of support for a grid leak resistance used in combination with the condenser.

7. A grid leak comprising a condenser having armatures of opposite polarity with integral extensions from the body of the con- 65

denser, a resistance element mounted between and supported by said extensions, the latter also serving as terminals for the condenser and resistance element.

8. A grid leak comprising a stack condenser having armatures of resilient material 70 extending from opposite sides of the stack, a resistance element mounted between and supported by said resilient extensions, the latter also serving as terminals for the grid leak.

Signed at Philadelphia in the county of Philadelphia and State of Pennsylvania, this 17th day of March, A. D. 1925.

CHARLES E. VAWTER.
